UNITED STATES PATENT OFFICE

153,298

DESIGN FOR A COMBINED DATE AND
WEATHER INDICATOR

Henry C. La Hue, South St. Paul, Minn.

Application March 26, 1947, Serial No. 137,890

Term of patent 14 years

(Cl. D74—5)

To all whom it may concern:

Be it known, that I, Henry C. La Hue, a citizen of the United States, residing at South St. Paul, county of Dakota, and State of Minnesota, have invented a new, original, and ornamental Design for a Combined Date and Weather Indicator, of which the following is a specification, reference being had to the accompanying drawing, forming part thereof:

Figure 1 is a front elevational view of a combined date and weather indicator showing my new design;

Figure 2 is a side elevational view of the same.

I claim:

The ornamental design for a combined date and weather indicator, as shown.

HENRY C. LA HUE.
